CHARLES T. DICKEY, OF ELIZABETH, NEW JERSEY, ASSIGNOR TO RODIC RUBBER CO., OF GARWOOD, NEW JERSEY, A CORPORATION OF NEW JERSEY.

TYPEWRITER PLATEN AND PROCESS FOR PRODUCING THE SAME.

Application filed June 4, 1928. Serial No. 113,674.

My invention relates to typewriter platens and refers particularly to platens which are practically noiseless during their employment.

5 The object of my invention is a typewriter platen in which the noise incident to operation is greatly reduced without affecting its writing, or impression, properties.

Typewriter platens have a hard smooth 10 external face to receive the type impacts and experiments have shown that this exterior portion of a platen must have particular and exact physical properties, in order to produce the best results.

15 The device of my invention is of such a character that this exterior portion may be of such chemical and physical composition and construction as to produce the desired results, and may be varied as desired, without 20 affecting the noise reducing properties of my platen.

It is evident, therefore, that the particular 25 elements of my invention may be successfully applied to any typewriter platen irrespective of the character of its outer, or operative portion.

I have found that the noise of a platen 30 incident to operation may be greatly reduced if it have an inner core of a rubber-treated fibrous material, and without limiting myself to such material, I prefer to use loose wool, or wool fibers, for this purpose.

In the accompanying drawings, illustrating 35 my device as produced from loose wool, similar parts are designated by similar numerals.

Figure 1 is a side view of one form of the 40 device of my invention, partly broken away to illustrate its several layers.

Figure 2 is a cross-section through the line 2—2 of Figure 1.

The particular form of the device of my 45 invention, as shown in the accompanying drawings, comprises an exterior layer of hard rubber 10 producing the impact face of the platen. Within the rubber layer is a core 11 consisting of loose wool, rubber and rubber cement within which is an inner lining of fabric 12.

50 The following is a process of my invention for the production of the illustrated platen:—Loose wool is worked in an unvulcanized rubber cement until thoroughly impregnated with the cement, and is then dried

to the proper consistency. It is then applied 55 to a mandrel covered with a fabric and calendered to the desired thickness. The vulcanized rubber is then applied to the exterior of the described mixture device and the entire device is then vulcanized. The fabrics 60 are not essential but I prefer to employ them, for ease of production and greater permanency of the produced platen.

I have found that a platen thus produced has valuable noise-reducing properties and 65 that the sound of the key impacts are greatly reduced without affecting the properties of the outer layer, or core, for purposes of typewriter use, and that its noise-reducing properties are greatly superior to those 70 possessed by a platen in which the inner core is of fabric construction.

I do not limit myself to the particular, size, shape, number, arrangement or material of parts as shown and described as these are 75 given simply as a means for clearly describing my invention.

What I claim is:—

1. In a process for the production of typewriter platens, the steps which comprise saturating a fibrous material with a rubber cement composition, forming a core therefrom, covering the exterior surface of the core with a layer of unvulcanized rubber and vulcanizing the device thus produced. 80

2. In a process for the production of typewriter platens, the steps which comprise saturating loose wool with a rubber cement composition, forming a core therefrom, covering the exterior surface of the core 90 with a layer of unvulcanized rubber and vulcanizing the device thus produced.

3. In a process for the production of typewriter platens, the steps which comprise saturating a fibrous material with a rubber cement composition, forming a core therefrom over a fabric, covering the exterior surface of the core with a layer of unvulcanized rubber and vulcanizing the device thus formed. 95

4. In a process for the production of typewriter platens, the steps which comprise saturating loose wool with a rubber cement composition, forming a core therefrom over a fabric, covering the exterior surface of the core with a layer of unvulcanized rubber and vulcanizing the device thus formed. 100

5. In a platen, in combination, an exterior

layer of vulcanized rubber, a core of loose fiber interior thereof impregnated with vulcanized rubber and a fabric lining interior of the impregnated core.

5 6. In a platen, in combination, an exterior layer of vulcanized rubber, a core of loose wool interior thereof impregnated with vul-

canized rubber and a fabric lining interior of the impregnated core.

Signed at Garwood in the county of Union **10** and State of New Jersey this 29th day of May, 1926.

CHARLES T. DICKEY.
